Eugene E. Crile, 1619 W. Mariette Ave., Phoenix, Ariz.
Filed Nov. 12, 1959, Ser. No. 852,424
12 Claims. (Cl. 212—63)

This invention relates to a crane and more particularly to a crane for use on trucks for loading and unloading the same; said crane being adapted to handle cubes of concrete blocks or other material and having its entire motivating and power mechanism on the boom structure thereof above the bed of a truck on which it is supported.

Cranes of conventional prior art construction which are employed to load and unload flat bed trucks generally include mechanism below the truck bed for actuating the crane and providing power for its operation. These cranes require a variety of mechanism which must be installed on the truck and operable in connection with the chassis thereof. Furthermore, such equipment is so located that it is difficult to service and maintain. Additionally, such equipment is ordinarily best suited to an installation on relatively heavy trucks.

The foregoing prior art structures are generally expensive from a standpoint of initial investment and further require installation facilities which are expensive.

Accordingly, it is an object of the present invention to provide a crane for loading and unloading trucks which may be installed on the upper surface of a truck bed without requiring any actuating means below the upper surface of the truck bed.

Another object of the invention is to provide a crane for loading and unloading truck beds which is provided with a swingable boom carrying means for powering the hoisting mechanism of the crane as well as the boom swinging mechanism of the crane.

Another object of the invention is to provide a crane having a boom swingable on a substantially vertical axis and carrying an engine which operates hydraulic means to power hoisting equipment on the boom and also to swing the boom around said vertical axis.

Another object of the invention is to provide a crane for loading and unloading flat bed trucks which is provided with a boom swingable about a vertical axis which carries an engine and power equipment on one of the boom supporting the hoisting mechanism whereby the engine and power equipment of the crane tends substantially to counter balance the end of the boom which supports the hoisting mechanism.

Another object of the invention is to provide a crane for loading and unloading flat bed trucks which is very simple and economical of construction and installation and maintenance.

Another object of the invention is to provide a crane wherein the boom thereof swings about a vertical axis and whereon all of the power mechanism required to operate hoisting mechanism and to swing the boom is carried on the boom itself.

Another object of the invention is to provide a crane for loading and unloading trucks having a novel hydraulic power mechanism totally supported on the swinging boom of the crane for operating hoisting mechanism and for swinging the boom of the crane about a vertical axis.

Another object of the invention is to provide a crane for loading and unloading flat bed trucks; said crane having a base adapted to be mounted on the upper surface of a flat bed truck and provided with extendable outriggers disposed to be extended horizontally and vertically in order to engage the ground and balance the truck when a heavy load is picked up laterally of the truck bed.

Another object of the invention is to provide a novel telescopic outrigger mechanism disposed in the base of a

2

crane which is totally disposed above the upper surface of a flat bed truck.

Further objects and advantages of the invention may be apparent from the following specification, appended 5 claims, and accompanying drawings in which:

FIG. 1 is a side elevational view of a crane constructed in accordance with the present invention and showing it mounted on the upper surface of a truck bed.

FIG. 2 is an enlarged fragmentary sectional view 10 taken from the line 2—2 of FIG. 1.

FIG. 3 is an elevational view of the mechanism shown in FIG. 2 taken from the line 3—3 of FIG. 2.

FIG. 4 is a fragmentary perspective view of the 15 outrigger mechanism of the present crane showing it extended laterally and to the ground for stabilizing a truck bed on which the crane is mounted.

FIG. 5 is an enlarged fragmentary sectional view taken from the line 5—5 of FIG. 1.

FIG. 6 is an enlarged fragmentary top or plan view 20 taken from the line 6—6 of FIG. 1.

FIG. 7 is an enlarged transverse sectional view of the boom of the crane taken from the line 7—7 of FIG. 1.

FIG. 8 is an enlarged transverse sectional view of the 25 boom of the crane taken from the line 8—8 of FIG. 1.

FIG. 9 is a fragmentary side elevational view of a modified form of the invention showing portions thereof broken away to amplify the illustration.

FIG. 10 is an enlarged fragmentary sectional view taken from the line 10—10 of FIG. 9.

FIG. 11 is an enlarged fragmentary top or plan view 30 of the modified structure of the crane taken from the line 11—11 of FIG. 9.

FIG. 12 is an enlarged fragmentary view of the 35 outrigger mechanism of the modified crane shown in FIG. 9 of the drawings; and

FIG. 13 is an enlarged fragmentary sectional view taken from the line 13—13 of FIG. 9.

As shown in FIG. 1 of the drawings, the crane is provided with a base 20 which is adapted to be secured on 40 the upper surface 22 of a conventional flat truck bed 24. Extending upwardly from the base is a vertical member 26 having a boom 28 mounted thereon and disposed to swing or pivot on a vertical axis.

The boom 28 carries a movable hoisting carriage 30 45 powered hydraulically by means of an engine 32 which is coupled with a hydraulic pump 29 and solenoid valve controls 34 which are operated by a remote switching mechanism 36.

It will be seen that the hydraulic power equipment including the engine 32 is at one end of the boom 28 while 50 the hoisting mechanism 30 is disposed near the other end whereby the power equipment tends to provide a certain degree of balance for the boom 28 about its pivotal axis which is concentric with the vertical member 26.

This member 26 is provided with angular braces 36 and 55 38. There being two of the braces 38, one on each side, which interconnects the vertical member 26 and one of the hollow tubular horizontal members 40. These hollow tubular members 40 are secured to a truck frame 42 by means of clamp bolts 44 which extend downwardly 60 through the bed 24 of the truck and are fixed by crossplates to the frame 42.

Telescopically mounted within the hollow tubular horizontal base members 40 are horizontally extendable hollow tubular members 46 having angle plates 48 on the 65 extending ends thereof. Between these angle plates 48 are legs 50 held thereon by pins 52. The lower ends of the legs 50 are provided with feet 54 which are disposed to rest on the ground outboard of the truck bed 24 in order to brace the truck bed against tilting action when 70 the boom 28 of the crane is cantilevered outwardly beyond the bed of the truck.

When the legs 50 are removed from the ground they may be released from the angle plates 48 by removing the pins 52 whereupon the legs 50 may be stowed in the hollow tubular members 46 which may be telescopically retracted into the hollow tubular base members 40 wherein they are retained during transit.

As shown in FIG. 3 of the drawings, a bearing housing 56 is rotatably mounted on the upper end of the vertical member 26 and carries the boom 28. The housing 56 is provided with an enlarged cylindrical bearing portion 58 which fits over roller bearing 59 on the vertical member 26. The vertical member 26 extends upwardly internally of the bearing tube 56 to carry the bearings and lend support thereto.

The boom 28 is preferably welded to the bearing housing 56 and is a cantilever boom of generally I beam construction.

As shown in FIG. 7 of the drawings, the boom 28 is provided with lower flanges 62 engaged by carriage rollers 64 which traverse the upper surfaces of said flanges 62. These rollers 64 are rotatably mounted on the carriage 30 which also carries guide rollers 68 mounted on vertical axis and engaging the edges of the flanges 62 in order to provide lateral stability of the carriage 30.

The carriage 30 is also provided with a pair of spaced pins 70 and 71 forming axles for sheaves 72 and 73 which are suspended near the lower portion of the carriage 30 as shown best in FIG. 1 of the drawings.

A cable 74 is anchored at one end 76 to the bearing housing 56 and this cable 74 passes over the sheave 73 and partially around a hoist cable sheave 78 suspended between the sheaves 72 and 73. The cable 74 also passes over the sheave 72 and extends around the end of the boom 28 in engagement with sheaves 80 and 82 which are rotatably supported between plates 84 at the outboard end of the boom 28.

The cable 74 then passes over a multiple sheave 84 fixed by means of brackets 86 to the upper outboard end of the boom 28. The cable 74 also passes over a multiple sheave structure 88 carried by a plunger 90 of a hydraulic cylinder 92 which is anchored by means of a pin 96. The opposite end of the cable 74 is anchored to the boom at 97.

The gussets 94 are disposed between the boom 28 and the bearing housing 56 and are welded thereto. Thus, the hydraulic cylinder 92 is maintained stationary while its plunger 90 is capable of moving the multiple sheave 88 relative to the stationary multiple sheave 84. The cable 74 being alternately and successively engaged with the multiple sheave structures 84 and 88 tends to multiply the longitudinal displacement of the cable 74 in comparison to the longitudinal movement of the plunger 90 of the hydraulic cylinder 92. Thus, the hoist sheave 78 may be raised a considerable distance with a comparatively lesser travel of the hydraulic cylinder plunger 90.

Fixed to the carriage 30 at 98 is one end of a cable 100 which passes over a multiple sheave 102 stationarily mounted on the side of the boom 28. This cable 100 also passes over a multiple sheave 104 carried by a plunger 106 of a hydraulic cylinder 108 stationarily mounted on the boom 28 by a pin 110 passing through the opposite end of the cable 100. The cable 100 is fixed to the multiple sheave 104 at 105 a mounting plate 111 which is preferably welded to the boom 28.

The sheaves 102 and 104 multiply movement of the cable 100 with respect to the movement of the plunger 106 of the hydraulic cylinder 108 so that this cable 100 is disposed to retract the carriage 30 along the flanges 62 of the boom 28 in a direction toward the vertical member 28 while another cable 112 is disposed to move the carriage 30 in the opposite direction.

This cable 112 is fixed to the carriage 30 at 114 and passes over a multiple sheave 116 fixed to the boom 28 and also passes over a movable sheave 118 carried by a plunger 120 of a hydraulic cylinder 122 stationarily

5

mounted by a pin 123 to an anchor member 124 which is preferably welded to the side of the boom 28. The cable 112 is fixed to the sheave 118 at 121. It will be seen that the hydraulic cylinder 122 is similar in action to the hydraulic cylinder 108 but moves the carriage 30 in the opposite direction toward the outboard end of the boom 28.

Carried by the bearing housing 56 is a frame 126 which supports the engine 32, a hydraulic pump driven thereby, an electrical battery 128, a hydraulic reservoir 130 and the solenoid valve assembly 34. Additionally, this frame 126 supports a hydraulic cylinder 132 which operates to rotate the boom 28 about a vertical axis concentric with the vertical frame member 26.

10

As shown in FIG. 2 of the drawings, the hydraulic cylinder 132 is provided with a plunger 134 carrying a cross head 136 on which a pair of sprockets 138 and 140 are rotatably mounted. A chain 142 is anchored to the frame 126 at 144 and passes over the sprockets 138 and 140 thence over an idler sprocket 146 stationarily mounted on the frame 126 by a pin 148. The chain 142 then passes over a sprocket 150 which is fixed to the vertical member 26. The chain then passes over another pair of sprockets 152 and 154 also carried by the cross head 136 actuated in connection with the plunger 134 of the hydraulic cylinder 132. These sprockets 152 and 154 are rotatably mounted on axles 156 and 158.

The opposite end of the chain 142 from its end 144 is stationarily fixed to the frame 126 by a bolt 160.

20

It will be seen that reciprocal action of the plunger 134 of the hydraulic cylinder 132 causes reciprocal movement of the chain over the sprockets 138 and 140 and 152 and 154 thereby causing relative rotational movement of the frame 126 about the axis of the sprocket 150 which is held stationarily on the vertical member 26 of the crane base. Since the frame 126 is fixed to the bearing housing 56 torque reaction is applied to this tube and thus the boom 28 is forced to pivot about the axis of the vertical member 26 of the base frame 20.

30

The battery 128 is used as a conventional means for starting the gas engine 32 and also is used to power the solenoid valves 34 which are controlled by a switching mechanism 36 to admit hydraulic fluid under pressure to the various hydraulic cylinders hereinbefore described. The switching mechanism 36 is provided with a plurality of buttons 37 which selectively may be used to operate the various solenoid valves and respective hydraulic cylinders hereinbefore referred to for moving the carriage 30 backwardly and forwardly, or for retracting the cable 74 to raise the hoist sheave 78, or to energize the hydraulic cylinder 132 and swing boom 28 about the vertical axis of the frame member 26.

40

In operation the crane of the present invention is completely powered by mechanism carried on the swinging boom of the crane. The base 20 provides a simple mount for the crane and may be attached to any flat bed truck without undue complications. This base also supports the telescopic members 46 which are arranged to brace the truck bed by means of the legs 50 having the feet 54 which are vertically adjustable to engage the ground laterally of the truck.

50

Thus, all of the elements necessary to convert an ordinary flat bed truck to a crane truck are provided in the crane of the present invention. The basic mechanism of the truck is not altered when the crane of the present invention is installed thereon and there is no power mechanism for operating the crane below the surface of the truck bed. Furthermore, the power mechanism including the engine 32 and other related equipment tends to counterbalance the boom 28 to a certain extent and also operates all of the carriage traverse mechanism as well as the hoisting mechanism and also the means for swinging the cantilever boom 28 about its vertical axis.

60

The use of hydraulic cylinders operated by an engine 55 on the boom provides a very compact means for obtain-

ing sufficient power to hoist heavy loads by means of the hoisting sheave 78. While maintaining the over all power and boom structure relatively compact and easy to service.

In the modified structure of the invention as shown in FIGS. 9 to 13, inclusive, of the drawings the base of the crane is adapted to rest on the upper surface 22 of a truck bed 24 similar to that shown in FIG. 1 of the drawings.

This base designated 162 is fixed to the lower end of a vertical member 164 and the base 162 is provided with three horizontal members 166 as shown in FIG. 12 of the drawings. These horizontal members are provided with angular braces 168 which are fixed at their upper ends to the vertical member 164.

Fixed to a pair of these braces 168 and directed toward opposite sides of the base 162 are spaced plates 170 between which outrigger legs 172 are each pivotally mounted on a pin 174 which extends through both plates 70.

The lower ends of the legs 172 are provided with feet 176 which are hinged thereto by pins 178. These feet 176 engage the ground and the legs 172 may be braced by a chain 180 having a clevis 182 coupled to the leg and having the opposite end of the chain coupled to an I bolt 184 fixed to the truck bed. Thus, the legs 172 may be prevented from spreading when a heavy load is applied thereto.

These legs 172 may be pivoted upwardly in the direction of the arrow as shown in FIG. 12 of the drawings and secured in the broken line position A when in transit. The pins 174 permit the legs 172 to be pivoted upwardly into said broken line position.

As shown in FIG. 13 of the drawings, the vertical frame member 164 is provided with a shoulder plate 186 fixed thereon. Supported on this plate is a roller bearing 188 which surrounds the circular in cross section structure of the vertical member 164. Mounted on the outer race of the roller bearing 188 is a sleeve 190 to which the lower end of a bearing housing 192 is fixed. Fixed to the upper end of the bearing tube 192 is a sleeve 194 in which the outer race of another large roller bearing 196 is supported. The inner race of this bearing 196 engages the periphery of the vertical member 164 and this upper race 198 is held in position by a bearing cap 200 secured to the vertical member 164 by means of bolts 202.

The bolts 202 also secure a sprocket 204 onto the upper end of the vertical frame member 164 which as hereinbefore described is held stationary on the frame or bed of the truck. It will be noted that the base of the modified structure of the invention is secured to the frame and bed of a flat bed truck in a similar fashion to that of the structure shown in FIG. 1 of the drawings.

Interposed between the bearing plate 200 and the ring 194 is a seal 206 and interposed between the shoulder plate 186 and the ring 190 is another similar seal 208. These seals 206 and 208 prevent foreign matter from reaching the bearings 188 and 196.

As shown in FIG. 11 of the drawings, a boom 210 is supported by the bearing housing 192. This boom as will be hereinafter described in detail is structurally triangular in cross section to withstand various loading including twisting moments.

The boom 210 is swingable about the axis of the sprocket 204 by means of a double ended hydraulic cylinder 212 having oppositely directed plungers 214 and 216. The cylinder 212 is fixed to the boom 210 and coupled to the ends of the plungers 214 and 216 by means of pins 218 and 220, respectively, is a chain 222.

The chain 222 passes over the sprocket 204 and also extends over a stationarily mounted sprocket 224 which is rotatable about a bearing shaft 226 held stationarily by a fixture 228 welded or other wise secured on the upper surface of the boom 210.

Reciprocal action of the plungers 214 and 216 causes torque reaction to be applied to the boom 210 around the axis of the fixed sprocket 204. Thus, the boom of the crane is pivoted.

Carried by the bearing tube 192 is a power equipment frame 230 which carries an engine, hydraulic pump, battery, hydraulic reservoir, solenoid valves and other equipment similar to that as shown in FIG. 1 of the drawings.

As shown in FIG. 10 of the drawings, the boom 210 is triangular in cross section and structurally arranged to resist twisting moments which may be applied when the truck being loaded and unloaded is located on a side hill and when the vertical frame member is tilted at an angle to the vertical.

Disposed internally of the boom 210 is a hydraulic cylinder 232 which is stationarily anchored to the bearing housing 192 by means of a pin 234. This hydraulic cylinder is provided with a plunger 236 having a multiple sheave 238 over which a cable 240 is engaged. This cable is also engaged over a multiple sheave 242 near the outboard end of the boom 210 and this cable also passes over sheaves 244 and 246 at the outboard end of the boom thence the cable 240 passes over sheaves 248 and 250 on a carriage 252 which is similar to the hereinbefore mentioned carriage 30. Between the sheaves 248 and 250, the cable 240 engages a hoisting sheave or pulley 254.

The sheave or pulley 254 serves as a component of a load-carrying means including a conventional block cube engaging fork, not shown, but which is a conventional device. Thus, the load-carrying means, of which the pulley 254 is a part, is normally below the power operated hydraulic components of the invention, even when the load-carrying means is in its loading position whereby the movement of the carriage 30 along the boom of the crane and during the slight swinging movement of the load, all of the power operated components are above the load and are not subject to damage thereby.

It will be understood that the loading of cubes of concrete blocks on a truck bed may be hazardous to surrounding equipment and for this reason, the power operated components, including the motor, the hydraulic cylinders and the actuating mechanisms, are all positioned above a loading position of the load-carrying means and the load so that such important equipment is not subject to damage by swinging or movement of the concrete blocks or the load-carrying means.

The carriage 252 is provided with rollers 256 which engage legs 258 and 260 of channels 262 and 264, respectively. These channels being fixed to the lower side of the boom 210. The carriage 252 is thus similar to the carriage 30 described in connection with the structure shown in FIG. 1 of the drawings.

Disposed between the channels 262 and 264 is a hydraulic cylinder 266 which is a double ended cylinder having a plunger 268 at one end and a plunger 270 at the other end.

Carried by the plunger 268 is multiple sheave 272 having a cable 274 engaged therewith. This cable 274 also passes over a multiple sheave 276 stationarily mounted on the bearing housing 192. The cable 274 is thus retracted by a multiple action over the sheaves 272 and 276 to move the carriage 252 in one direction while a cable 278 is engaged over the multiple sheave 280 carried by the plunger 270. This cable 278 is also engaged over a multiple sheave 282 near the extending end of the boom and stationarily mounted. Thus, the carriage being coupled to the cable 278 is powered in the opposite direction from that caused by actuation of the cable 274.

It will be apparent to those skilled in the art that the operation of the boom 210 is similar to the operation of the boom 28 and that this boom carries all of the power equipment necessary to swing it and also to op-

erate the hoisting mechanism for lifting various loads to which the crane may be applied.

It will be further obvious to those skilled in the art that various modifications of the present invention may be resorted to in a manner limited only by a just interpretation of the following claims.

I claim:

1. In a crane the combination of: a base frame adapted to be secured on a truck; horizontal members on said base frame; arms horizontally and telescopically connected to said horizontal members; vertical legs secured to said arms and having feet engageable with the ground to provide an outboard brace and support for said truck; and a crane boom pivoted on said base frame about a vertical axis, said boom of a length to extend beyond said base frame and outwardly of said truck; a hoist carriage movable back and forth longitudinally on said boom; flexible means coupled to said hoist carriage and disposed in opposite directions longitudinally of said boom; means connected to said flexible means for actuating said hoist carriage in said back and forth directions; a lowermost portion and all the operating structure of said crane, at said base, disposed to be supported on a truck bed and thereabove, said horizontal members also disposed to be located above a truck bed when said crane is supported thereon.

2. In a crane the combination of: a base frame adapted to be secured on a truck; horizontal members on said base frame; arms horizontally and telescopically connected to said horizontal members; vertical legs secured to said arms and having feet engageable with the ground to provide an outboard brace and support for said flat bed truck; and a crane boom pivoted on said base frame about a vertical axis, said boom of a length to extend beyond said base frame and outwardly of said flat bed truck; a hoist carriage movable back and forth longitudinally on said boom; first cable means coupled to said hoist carriage and disposed in opposite directions longitudinally of said boom; a first hydraulic actuating cylinder means having a plunger connected to said cable means for actuating said plunger to move said hoist carriage in said back and forth directions; said hoist carriage having a pair of spaced pulleys; a second cable means engaged over said pulleys and having its intermediate portion hanging downwardly between and below said pulleys in a loop; a lift pulley disposed in said loop; and third means for drawing said second cable means over said pulleys to reduce the vertical length of said loop and thereby raise said lift pulley; a lowermost portion and all the operating structure of said crane, at said base, disposed to be supported on a truck bed and thereabove, said horizontal members also disposed to be located above a truck bed when said crane is supported thereon.

3. In a crane the combination of: a base frame adapted to be secured on a truck; horizontal members on said base frame; arms horizontally and telescopically connected to said horizontal members; vertical legs secured to said arms and having feet engageable with the ground to provide an outboard brace and support for said truck; and a crane boom pivoted on said base frame about a vertical axis, said boom of a length to extend beyond said base frame and outwardly of said truck; a hoist carriage movable back and forth longitudinally on said boom; first cable means coupled to said hoist carriage and disposed in opposite directions longitudinally of said boom; a first hydraulic actuating cylinder means having a plunger connected to said first cable means for actuating said plunger to move said hoist carriage in said back and forth directions; said hoist carriage having a pair of spaced pulleys; a second cable means engaged over said pulleys and having its intermediate portion hanging downwardly between and below said pulleys in a loop; a lift pulley disposed in said loop; and third means for drawing said second cable means over said pulleys to

reduce the vertical length of said loop and thereby raise said lift pulley; said third means comprising a second hydraulic cylinder on said boom and having a plunger connected to said second cable means; and a third pulley means at the extending end of said boom to guide and support said third cable around said extending end from the top of said boom to the bottom thereof; a lowermost portion and all the operating structure of said crane, at said base, disposed to be supported on a truck bed and thereabove, said horizontal members also disposed to be located above a truck bed when said crane is supported thereon.

4. In a crane the combination of: a base frame adapted to be secured on truck; horizontal members on said base frame; arms horizontally and telescopically connected to said horizontal members; vertical legs secured to said arms and having feet engageable with the ground to provide an outboard brace and support for said truck; and a crane boom pivoted on said base frame about a vertical axis, said boom of a length to extend beyond said base frame and outwardly of bed truck; a hoist carriage movable back and forth longitudinally on said boom; first cable means coupled to said hoist carriage and disposed in opposite directions longitudinally of said boom; a first hydraulic actuating cylinder on said boom, and having a plunger connected to one of said first cable means for actuating said plunger to move said hoist carriage in said back and forth directions; said hoist carriage having a pair of spaced pulleys, a second cable means engaged over said pulleys and having its intermediate portion hanging downwardly between and below said pulleys in a loop; a lift pulley disposed in said loop; third means for drawing said second cable means over said pulleys to reduce the vertical length of said loop and thereby raise said lift pulley; said first means comprising a second hydraulic cylinder on said boom and having a plunger connected to said second cable means; and second pulley means at the extending end of said boom to guide and support said second cable means around said extending ends from the top of said boom to the bottom thereof; and multiple sheave blocks and cable means intermediate the plunger of said second hydraulic cylinder and said first pulley means to provide a mechanical advantage for said second hydraulic cylinder in its actuation of said third cable; a lowermost portion and all the operating structure of said crane, at said base, disposed to be supported on a truck bed and thereabove, said horizontal members also disposed to be located above a truck bed when said crane is supported thereon.

5. In a crane the combination of: a base frame adapted to be secured on the upper surface of a flat bed truck; horizontal members on said base frame; arms horizontally and telescopically connected to said horizontal members; vertical legs secured to said arms and having feet engageable with the ground to provide an outboard brace and support for said flat bed truck; and a crane boom pivoted on said base frame about a vertical axis, said boom of a length to extend beyond said base frame and outwardly of said flat bed truck; a hoist carriage movable back and forth longitudinally on said boom; first cable means coupled to said hoist carriage and disposed in opposite directions longitudinally of said boom; a first hydraulic actuating cylinder on said boom, said cylinder having a plunger connected to said cable means for actuating said plunger to move said hoist carriage in said back and forth directions; and multiple sheave and cable means intermediate said hoist carriage and said first hydraulic cylinder to provide a mechanical advantage therefore; a lowermost portion and all the operating structure of said crane, at said base, disposed to be supported on a truck bed and thereabove, said horizontal members also disposed to be located above a truck bed when said crane is supported thereon.

6. In a crane for trucks the combination of: a base for

said crane adapted to be supported by a truck; a boom supported on said base and disposed to swing on a vertical axis; a motor carried by said boom; first means operable by said motor for swinging said boom about a vertical axis; and vertically movable load carrying means suspended from said boom, said motor and said first means both disposed above a loading position of said vertically movable load carrying means and articles carried thereby, all the structure of said base disposed above a bottom plane of said base which is adapted to rest on a truck bed.

7. In a crane for trucks the combination of: a base for said crane adapted to be supported on a truck; a boom supported on said base and disposed to swing on a vertical axis; a motor carried by said boom; first means operable by said motor for swinging said boom about a vertical axis; a carriage movable longitudinally of said boom; second means operable by said motor for moving said carriage longitudinally of said boom; third means coupled to said carriage and operable by said motor for hoisting articles relative to said carriage; and vertically movable load carrying means of said third means suspended from said carriage, said motor, first means and second means all disposed above a loading position of said vertically movable load carrying means and articles carried thereby, all the structure of said base disposed above a bottom plane of said base which is adapted to rest on a truck bed.

8. In a crane for trucks the combination of: a base; a vertical member extending upwardly therefrom; a boom swingable about a substantially vertical axis of said vertical member; a motor carried on said boom; a pressure fluid means operable by said motor; a pressure fluid cylinder on said boom and having a plunger extendable and retractable relative thereto; flexible means coupled to said plunger; second means fixed on said vertical member and engaged by said flexible means to provide torque reaction of said boom about the vertical axis of said vertical member; and vertically movable load carrying means suspended from said boom, said motor, pressure fluid means, pressure fluid cylinder, flexible means and said second means all disposed above a load carrying position of said vertically movable load carrying means and articles carried thereby, all the structure of said base disposed above a bottom plane of said base which is adaptable to rest on a truck bed; means coupling said pressure fluid cylinder to said pressure fluid means for operating said pressure fluid cylinder by said motor, said second means operable by said motor.

9. In a crane for truck beds the combination of: a base; a vertical member extending upwardly therefrom; a boom swingable about a substantially vertical axis of said vertical member; a motor carried on said boom; pressure fluid means operable by said motor; a pressure fluid cylinder on said boom and having a plunger extendable and retractable relative thereto; a first flexible means coupled to said plunger; a second means fixed on said vertical member and engaged by said first flexible means to provide torque reaction of said boom about the axis of said vertical member; a second pressure fluid cylinder having a movable plunger; a carriage movable longitudinally of said boom; and second flexible means coupled to said second cylinder for actuating said carriage on said boom; and vertically movable load carrying means suspended from said carriage, said motor, pressure fluid means, first and second pressure fluid cylinders, said first and second flexible means and said second means all disposed above a load carrying position of said vertically movable load carrying means and articles carried thereby, all the structure of said base disposed above a bottom plane of said base which is adapted to rest on a truck bed, all of said pressure fluid cylinders and said flexible means coupled to and operable by said motor.

10. In a crane for truck beds the combination of: a base; a vertical member extending upwardly therefrom; a boom swingable about a substantially vertical axis of said vertical member; a motor carried on said boom; pressure fluid means operable by said motor; a pressure fluid cylinder

der on said boom and having a plunger extendable and retractable relative thereto; a first flexible means coupled to said plunger; a second means fixed on said vertical member and engaged by said first flexible means to provide a torque reaction of said boom about the axis of said vertical member; a second pressure fluid cylinder having a movable plunger; a carriage movable longitudinally of second boom and said flexible means coupled to the plunger of said second cylinder for actuating said carriage on said boom; a third pressure fluid actuating cylinder supported on said boom and having an extendable and retractable plunger; third flexible means coupled to said last mentioned plunger and supported intermediate its ends on said carriage for hoisting articles relative thereto; and vertically movable load carrying means suspended from said carriage, said motor, pressure fluid means, first means, second and third pressure fluid cylinders, said first, second and third flexible means and said second means all disposed above a load carrying position of said vertically movable load carrying means and articles carried thereby, all the structure of said base disposed above a bottom plane of said base which is adapted to rest on a truck bed, all of said pressure fluid cylinders and said flexible means coupled to and operable by said motor.

11. In a crane for loading and unloading trucks the combination of: a normally vertical means adapted to be supported on a truck; a normally horizontal boom pivotally mounted on said vertical means and on a normally vertical axis; a motor on said boom; first means operable by said motor and disposed to swing said boom about said vertical axis; a carriage movable longitudinally of said boom; second means operable by said motor for moving said carriage back and forth on said boom; flexible means retractably suspended from said carriage; third means operable by said motor for retracting said flexible means relative to said carriage, said motor, first means, carriage, second means, flexible means and third means all disposed to swing above and clear a load placed on said truck by said crane; and vertically movable load carrying means of said third means suspended from said carriage, said motor, first, second, and third means all disposed above a loading position of said vertically movable load carrying means.

12. In a crane for trucks the combination of: a base for said crane adapted to be supported on a truck; a boom supported on said base and disposed to swing on a vertical axis; a motor for swinging said boom about a vertical axis; a carriage movable longitudinally of said boom; second means operable by said motor for moving said carriage longitudinally of said boom; third means coupled to said carriage and operable by said motor for hoisting articles relative to said carriage, said boom, motor, first, second, and third means all disposed to swing above and clear a load placed on said truck by said crane; and vertically movable load carrying means of said third means suspended from said carriage, said motor and said second means disposed above a load carrying position of said vertically movable load carrying means and articles carried thereby.
